UNITED STATES PATENT OFFICE

2,353,145

X-RAY MACHINE

George H. Chamberlain, Jr., San Jose, Calif.

Application April 12, 1941, Serial No. 388,235

17 Claims. (Cl. 250—61.5)

This invention relates to an improved X-ray machine.

Besides the older type of X-ray machine which is capable of operation in only the familiar, conventional manner, there has been also some comparatively recent development, both here and abroad, along the line of an X-ray machine of the general type shown in the U. S. Patents to Kleffer, No. 1,954,321, April 10, 1934, No. 2,167,114, July 25, 1939, and No. 2,167,116, July 25, 1939.

As will be understood from the above-cited patents, attempts have been made to virtually focus the rays of the X-ray tube with respect to a body section, that is a layer of the body, which it is desired to radiograph, the purpose being to obtain a clearer image.

It is understood, of course, that in this device there is not employed any principle of optics but there is accomplished the same purpose as in the focusing of an optical system and therefore the word "focus" is here used merely as a means of convenience in affording a clear understanding of the purpose of this machine and the effect obtained therewith.

Briefly, the general principle involved in this comparatively recent development is that the tube and sensitive film are moved during exposure in such manner that the roentgenographic shadow of a selected body section remains stationary on the moving film while the shadows of all other sections have a relative displacement on the film and are consequently blurred varying amounts depending principally upon the distance of such planes from that of the selected body section.

An examination of the prior art shows that while, to a large extent, the theory embodied therein is substantially correct, the mechanism is either too complicated in both construction and operation for practical purposes, or in some instances the mechanism is not wholly dependable, or it is not capable of sufficiently wide adaptability to different technique, or it is too costly for general adoption and use. Furthermore, the principle of operation in some of the prior devices is not sound.

It is therefore the object of the present invention, in a general way, to devise a method and machine for taking radiographs of the type above referred to, that is sound and feasible in principle and not complicated but comparatively simple and extremely practical in construction and operation.

Another object is to devise such a machine

that is capable of operation according to the principle above referred to, or can be alternately used at any time in the same manner as the older conventional type of X-ray machine and in an efficient manner.

It is also an object to devise such a machine that is readily adaptable to various technique, which is made possible by my particular system of construction and adjustability.

10 A more specific object is to devise an efficient and feasible form of machine structure in which there is produced synchronous circular motion of the tube and cassette so as to maintain the target of the tube and the cassette in parallel flat planes during such movement.

Another specific object is to devise such a machine in which there can be produced a synchronous spiral motion for the tube and cassette in a feasible and efficient manner for the purpose of blurring the shadows outside of the objective or nodal plane in an even more nearly complete manner.

15 A further object is to devise such a machine in which there is provided a means of increased amplitude and an improved means for varying the amplitude at any time, this means co-operating also with the spiral operation whenever employed.

20 A more specific object is to provide a low center of gravity in such a machine structure and in the arrangement of the base support and drive connection at the bottom part of the machine.

25 A still further feature of my present machine consists of the parallelogram form of operative connections between the drive means and the cassette and tube, whereby there is obtained comparative simplicity and dependability of construction and operation in the manner intended. This also constitutes an object of my present invention.

Another object is to provide, in such a machine, an improved adjusting means for the tube for use in the taking of stereoscopic pictures.

30 Another object is to provide such a machine with means whereby the tube may be adjusted through ninety (90) degrees so as to occupy vertical position for taking a radiograph of a patient in an erect or standing position, there being provided suitable and effective means for supporting the tube in either position.

Another object resides in the provision of an improved means of adjustment of the objective

plane, this feature also contributing to the stability of the machine structure.

Another object is to provide an improved form of grid.

Another object is to provide a convenient means whereby the position of the patient may be changed with respect to the projection of the rays from the tube.

It is also an object of this invention to devise such a machine structure that possesses all of these and other improved features and that can be manufactured and sold at a comparatively reasonable price.

Other objects will appear from the following description and claims when considered together with the accompanying drawings.

Fig. 1 is a perspective view of my present improved machine;

Fig. 2 is a sectional view showing the lower part of the operating mechanism;

Fig. 3 is a side elevation corresponding substantially to Fig. 2 except that it is at ninety (90) degrees thereto;

Fig. 4 is a detail view taken on line 4—4 of Fig. 2;

Fig. 5 is a top plan view of the mechanism which permits stereoscopic adjustment of the tube;

Fig. 6 is an elevation thereof;

Fig. 7 is a view taken on line 7—7 of Fig. 5;

Fig. 8 is a partial plan view of my improved grid, partly broken away;

Fig. 9 is a view taken on line 9—9 of Fig. 8;

Fig. 10 is a more or less diagrammatic elevation of the machine;

Fig. 11 is a front elevation illustrating the roller adjustable bed for supporting the patient;

Fig. 12 is a view taken on line 12—12 of Fig. 11;

Fig. 13 is a partial detail view illustrating a modification of the spiral motion drive means;

Fig. 14 is a sectional view of the locking lever mechanism; and

Fig. 15 is an enlarged view of the lower part of Fig. 1.

It is to be understood that the present forms of disclosure are merely for the purpose of illustration and that there may be devised various modifications thereof without departing from the spirit of the invention as herein set forth and claimed.

Upon the base 1 there is fixed the pair of parallel uprights 2 upon which is adjustably mounted the transverse support 3 for the universal joint assembly 4. The support 3 is adjusted in its elevation by means of racks 5 on the uprights 2 and companion pinions on the rotary shaft 6 which has the wheel 7 for operation thereof. The scale 8 may be employed for indicating the elevation of the support 3. This means of adjustment is for the purpose of varying the elevation of the objective plane in which is located the nodal point corresponding to the center of the universal joint connection 9 of the assembly 4. Through the tubular castings of the assembly 4 there extend the parallel posts 10, the assembly 4 being adjustable therealong in the manner explained. As will be understood, the body section which it is desired to radiograph, will be placed in the plane of the nodal point of the machine, which is here indicated at 9. The true nodal point is, of course, within the body of the patient and in the same horizontal plane with point 9.

The lower ends of the posts 10 have transverse axial bearing connection in the cross arm 11

which has bearing at ninety (90) degrees thereto in the yoke member 12 having swivel connection about a vertical axis in the threaded portion 13 of the slidable saddle. Co-operating with the said threaded portion 13 is the companion screw-threaded shaft 14 which is mounted transversely of the turn-table 15, the saddle having a block 16 on the underside of the threaded portion 13 for slidable adjustment within the transverse slot 11 in the turn-table 15. The purpose of this diametrical adjustment is to vary the amplitude, as will be more fully understood from the following. The screw 14 may be adjusted manually by means of the hand wheel 18 so as to thereby set the saddle at the point corresponding to the radius of operation desired for the turn-table. The saddle is slidable upon the bronze ways 16a and is guided between the steel gibbs 16b, one of which can be tightened by means of the locking lever 19 for releasably securing the saddle in the position to which adjusted.

The turn-table 15 is rotated by the electric motor 20 which has belt drive connection 21 with the pulley 22 on the shaft 23 which in turn has drive engagement with the annular worm gear 24 attached to the bottom of the turn-table. The auxiliary shaft 25 is a continuation of shaft 23. By manipulation of hand-wheels 18 and 26, the posts 10 can be brought to a rigid vertical position, when it is desired to take a radiograph according to the older conventional manner, as above referred to.

Also, with my machine it is possible to take conventional radiographs from practically any angle without having to place the patient in an angular position, which of course is very difficult with the previous equipment. In such case, the saddle will be positioned at the proper point upon the turn-table according to the angle desired.

Fixedly connected to the cross-arm 11, midway thereof, is the supporting extension or axle 27 which is adapted to move bodily with the yoke member 12 and every point of which describes a circle corresponding to that of the pivotal axis of said yoke member.

The axle 27 has the diametrically opposed yoke arms 28 fixedly secured thereto by means of the taper pin 28a and extending therefrom so as to afford fixed axial rotatable bearing for the transversely disposed shaft 29 which passes through yoke arms 28. To the outer ends of shaft 29 there are pivotally connected the lower ends of the upright rods 30 for movement at ninety (90) degrees to the axis of arms 29. The rods 30 at their upper ends have the same kind of pivotal connection with the ends of the transverse rod 31 which extends through the yoke arms 32 and at ninety (90) degrees to the axis of the shaft 33 so as to permit axial rotatable movement with respect thereto. The yoke member 32 is fixed to the end of the shaft 33 about which there is axial rotatable bearing of the cross arm 34 attached to the posts 10. Thus there is provided what is to be recognized as a parallelogram comprising the upper and lower parallel arms 29 and 31 and the upright parallel rods 30.

The brackets 35 are suspended from the transverse shaft 31 and support the rigid frame 36 from the cassette carriage 37. This frame is clamped to the shaft 33, as indicated at 33a, so as to assist in maintaining the frame in a fixed horizontal plane, the shaft 33 occupying position 70 in a fixed parallel relation to the fixed hori-

horizontal axis 27, as above explained. The supporting frame 36 is of sufficient extent that the cassette will occupy position directly beneath the point of emission of the Roentgen rays and also beneath the position to be occupied by the patient in the objective plane, as will be understood.

The yoke arms 38 on the end of the axle 27 afford transverse axial bearing for the lower end of the upright rod 39 which extends parallel with the posts 18 and which has transverse axial bearing at its upper end with the yoke 40a which is secured by means of the taper pin 40b to one end of transversely and substantially horizontally disposed axle 40 for supporting the bracket of the X-ray tube.

The upper ends of the posts 18 are secured in the tubular castings 18a and the adjustable bracket 41 which forms part of a universal joint assembly through which the shaft 40 extends and has universal bearing at 40c. This universal joint assembly is substantially the same as the one at the lower ends of posts 18 and also the one through which the shaft 33 extends and also the one of which the joint 9 forms part. Since rod 39 always maintains the same attitude as the posts 18, it follows that shaft 40 has no movement with respect to its own axis.

Casting 41a is secured to the end of shaft 40 by means of a nut 41b on the end of the shaft and a removable taper pin 41c which can be withdrawn when it is required to turn the tube to a vertical position for remote stereo-radiographs, for instance. Thus, as stated, shaft 40 does not rotate upon its own axis but simply has a raising and lowering movement with relation to the universal joint assembly through which it extends. Obviously, shaft 40 maintains a horizontal attitude as do also shafts 27 and 33.

Extending from the casting 41a are the parallel horizontally disposed rods 42 which co-operate with the companion rods 43 attached to the X-ray tube 44 for support of the same. The flat rollers 46 are mounted upon the end clamp means of the cross bracket 47 extending as a brace means between the rods 43; and these rollers 46 have rolling engagement with the flattened sides of the rods 42. Likewise, the rollers 48 are mounted upon the end clamp means of the cross bracket 49 extending as a brace means between the rods 42; and these flat rollers 48 have rolling engagement with the flattened sides of the rods 43. This roller engagement permits adjustment of the X-ray tube for taking stereoscopic pictures and facilitates adjustment of the tube through ninety (90) degrees for taking a radiograph of a patient in an erect or standing position. Also, the transverse rods of the cross brackets 47 and 49 afford a means for accurately adjusting the rollers in their contact with the flattened ways of the rods 42 and 43.

There is a plunger rod 51 extending rearwardly from the tube bracket 50 and provided with a plunger 53 within the air cylinder 54 to serve as a pneumatic shock absorber.

The coil springs 55 are connected at their ends to the tube bracket 50 and the transverse bracket 41a within which the rods 42 are mounted, and they tend to move the X-ray tube inwardly or towards the left, as viewed in Figs. 5 and 6 of the drawings.

For the purpose of maintaining the tube at all times in proper angular position during synchronous operation of the tube and cassette in the manner above explained, there is provided the rod 58 which is pivotally connected at its one end to

the rod 38 and at its other end to the tube cone by means of the yoke member 58b, so as to constitute a parallelogram with the supporting means for the X-ray tube, as will be understood from Figs. 1, 6 and 10. This feature will be more fully explained below.

With this machine it is possible to take stereolaminagraphs, that is when the patient is lying upon the table, the circular movement of the tube

10 and cassette being employed in connection therewith, and it is possible also to take stereoscopic pictures of the patient in standing position. When, however, stereoscopic pictures are being taken of the patient in standing position, the means for producing circular movement of the tube and cassette will not be employed but the machine will be used for taking conventional stereoradiographs in the same manner as the older conventional type of X-ray machine.

15 The X-ray tube can be moved outwardly, or towards the right as viewed in Figs. 5 and 6, when it is desired to take stereoscopic pictures, and there is provided a longitudinally movable horizontal latch pin 56 which will be engaged in 20 a suitable aperture 56a in the slidable frame of the X-ray tube so as to hold the same in extended position during taking of one of the stereoscopic pictures. Then when it is desired to take the other companion picture, the latch 56 can be 25 withdrawn by means of solenoid 57, the energization of which may be controlled by a manually operated switch at any desired point. Immediately upon withdrawal of the latch 56, the springs 55 will cause the tube to move to its other position by means of the slidable engagement above described, such movement being cushioned by the pneumatic shock absorber. The tube is shown in middle position in Figs. 5 and 6.

30 There is also a telescopic connection 58a in the rod 58 and I have provided also a solenoid 58d for actuating the lock 58c which will hold the portion 58a locked in extended position, this solenoid being adapted for remote control by the same switch that is provided for solenoid 57 so 35 that these two solenoids can be operated at the same time. One of the recesses into which the lock 58c may engage is indicated at 58e.

40 My improved stereoscopic structure is of compact, stable form and affords an efficient means 50 of support for the tube in such an arrangement.

45 By virtue of the double roller engagement 46 and 48, (Fig. 7), the entire bracket of the X-ray tube can be turned so as to occupy position at ninety (90) degrees to that indicated in the drawings, in case it should be desired to take a radiograph of the patient in standing position for instance. As will be seen, the present arrangement will permit stereoscopic radiographs to be taken when the X-ray tube occupies either position, there being an effective roller engagement 55 in both cases, as will be apparent from the present disclosure, and such means of engagement is equally efficient and dependable in both instances.

60 The shaft 27 assumes horizontal position by reason of the fact that it has bearing in the yoked spindle 12. Attached to shaft 27 by means of a taper pin is the flanged collar 27a which serves as a means of adjustment of cross shaft 29 in

65 horizontal position and also as a means of keeping shaft 27 from rotating upon its own axis within the yoke 12. Having adjusted shaft 29 to horizontal position, shaft 31 can then be adjusted to horizontal position by adjusting the turnbuckles on rods 30. The rods further serve

as a means of adjusting the cassette carriage 37 to horizontal position in two planes. That is, by adjusting rods 30 to equal length, there is eliminated any tipping of the cassette carrier 37 either way in line with the table; and by adjusting both rods 30 to the proper length, there is avoided any tipping of the cassette carrier 37 in the other direction or cross-wise of the table.

As a means of setting and securing the flanged collar 21a, I have provided the adjustable connection as indicated in Fig. 4. The flanged collar 21a has elongated holes 21b through which extend the machine cap screws 21c. With the machine cap screws 21c loosened, the axle 21 can be turned so as to properly position the shaft 29, whereupon the cap screws are then tightened so as to secure the axle in such position.

The tie-plates 10a, which brace the posts 10, serve to prevent the axle from wobbling, although primarily they prevent the assembly of posts 10 and the universal joints from developing a reciprocal torque action which might otherwise be set up by swinging the tube in a circle from the lower end of its long arm. That is, these tie-plates 10a keep the axles 21, 33 and 40 in perfect parallel relation which is vital in having the center ray of the tube always follow the same point on the film, while the axle shaft that passes through the universal joint assembly 9, the ends of which are supported in the mid-way castings of the assembly, indicated at 8, serves to stabilize the moving structure as it is propelled by the vertical supporting spindle of the yoke 12.

In Fig. 11 I have indicated an opening 66a for loading the cassette 60. The grid, which in the present form of disclosure, will occupy fixed position, may be attached to the rigid base or to the under-side of the table, directly over the cassette, and is indicated by reference numeral 61.

The details of my present improved form of grid 61 are illustrated in Figs. 8 and 9 of the drawings. This grid, which occupies fixed position immediately above the film, comprises the spaced parallel lead ribbons 61a between which are arranged the spacing elements 61b. In my present form of grid, the lead ribbons have been drawn through crimping rollers so as to form diamond-shaped cells when placed together with a thin spacer therebetween. For instance, the lead grid elements, before being crimped, may be about from one-sixteenth to one-eighth of an inch wide and about one-sixty-fourth of an inch thick; while the spacers may be about from one-thirty-second to one-sixty-fourth of an inch thick. In the present illustration, the grid elements are greatly exaggerated for the sake of a clearer understanding. My assembly of grid and spacer elements is encased between two thin aluminum plates which also serve as a filter medium, these plates being indicated by reference numeral 61c. As will be understood, the spacer elements are of a material that is more or less radio-transparent, as for instance "Micarta" which is made of paper or linen impregnated with varnish, while the grid elements are decidedly radio-opaque. The thickness of the grid elements may vary.

In the conventional type of X-ray machine, it is necessary to move the grid across the face of the film during the exposure lest an image of the grid lines show upon the developed film. Theoretically, the ideal grid would be one of minute cellular structure which would give maximum absorption of secondary rays and would also leave no line pattern on the developed film.

75

The grid here is located in neither the nodal plane nor in direct contact with the film; and, since the tube and film are both moving during exposure, the image of the grid will not be recorded upon the film. Then, in effect, it has a relative motion and can occupy fixed position. Furthermore, my particular form of grid has the effect of giving uniform absorption of secondary rays and thus produce uniform densities over the film. Because of the cellular structure of my grid, it provides openings from wider angles with the same effective area of absorption surface, which is a substantial approach towards the ideal situation as above referred to.

I have provided also an improved means for conveniently bringing in line with the center ray of the tube the particular part of the patient's body which is under examination, as for instance the head, the torso or the feet. In the present embodiment of this feature, the lower part of the machine structure, including the cassette carrier, is enclosed within a stationary base or casing 63 and upon the top of this casing there is arranged a readily movable bed 63a which has rollers 63b for facilitating such movement thereof while the patient occupies position thereon.

Instead of using the base or casing as a support for the permanently incorporated bed 63a, there might be provided a separate bed upon the floor for properly positioning with respect to the cassette carrier so as to support a readily adjustable roller-top upon which the body of the patient might be placed. Or, the regular table type of wheeled support for the patient might be moved into proper position over the casing, thereby relieving the handling of the patient.

There has been an attempt in the prior art to provide a spiral path of movement for the tube and the cassette carrier for the purpose of blurring the shadows outside of the objective plane more completely and thereby produce a relatively clearer image of the body section in the objective plane. However, so far as any such prior disclosure is concerned, it has not been possible to accomplish such blurring of the shadows without at the same time sacrificing some of the clarity of the radiographed image and without seriously reducing amplitude also. This has been due to the comparatively limited amplitude that has been possible in the prior machines. In the present machine however, there is provided means of comparatively increased amplitude which is made possible by the particular structure and arrangement of the mechanism including the slide saddle 16 and the companion diametrical slot 17 in conjunction with the adjustability of the nodal point. By virtue of the very nature and geometry of my machine structure, it follows that the greater the amplitude, the thinner and clearer the objective layer or plane.

When it is desired to employ the spiral arrangement, there will be effected an automatic continuous movement of the saddle along the screw 14 so as to thereby cause the same to move along the slot 17 and thereby effect a continuously changing radius of the circular movement and thus produce a spiral movement during the taking of the radiograph.

In the present disclosure, this is accomplished by a mechanism which can be thrown into and out of operation at will, as indicated in Fig. 2. The ring or track 65a has coarse screw-threaded adjustable engagement with the annular flange 65 on the base plate 1a and is beveled at the

upper edge thereof and is adapted to be engaged by the correspondingly beveled rotatable disk or wheel 67 which is fixed upon the screw-threaded shaft 14. When it is desired to turn the shaft 14 in one direction and to thus move the saddle in the corresponding direction, the ring 65a is raised into engagement with its wheel 67 by means of the pedal-operated lever mechanism 68. The saddle can be moved in the opposite direction by reversing the direction of the reversing type motor which will be employed for operating pulley 22. This electric motor will have proper limit switches and controlling devices.

The casing 65 which surrounds the worm gear will serve as an oil retainer.

If so desired, there might be interposed between the wheel 67 and the screw 14 a combination of gears for the purpose of changing the speed of the shaft with respect to that of the turn-table. Such a gear combination is here indicated in a general way as being enclosed within the housing 16a indicated in Fig. 13.

Theoretically it might appear to be necessary to provide an automatic means for varying the nodal point according to and in consonance with the automatic change in amplitude incident to the spiral movement, but in actual practice this is not necessary.

In this connection, it should be noted that with my continuous diametrical slot 17 it is possible to obtain an amplitude adjustment to any desired degree and my present device is not limited to an adjustment at only certain spaced intervals as in known instances of the prior art.

As will be understood, a change in the objective plane would cause a corresponding change in the amplitude but this can be compensated for by making any desired change in the amplitude by adjustment of the saddle along the slot 17. In this connection, my present means of amplitude adjustment is especially advantageous since the saddle can be moved to an extent corresponding exactly with any degree of change of the nodal point, as above explained.

In my present machine structure there can be identified a compound parallelogram linkage in connection with the operation of the cassette carrier; one of these parallelograms comprising the arms 29 and 31 and the rods 30, the other comprising the axle 27, the rods 30, shaft 33 and the posts 10. It is by means of this compound parallelogram linkage that the cassette carrier is maintained in a flat horizontal plane while being moved in a circular path within said plane.

Another parallelogram linkage comprises the rod 29, the axle 40, the posts 10 and axle 27. This parallelogram linkage serves to compensate for the tendency of the tube to dip upwardly and downwardly in a vertical plane as it would do except for the present provision. With this means, the target of the tube is maintained in a flat horizontal plane as it travels in a circular path within said plane in synchronism and co-ordination with the simultaneous movement of the cassette carrier, as above described. Thus the target and the cassette are both moved in flat horizontal planes that are parallel to each other and this relationship is maintained at all times throughout all adjustments of the nodal plane.

There is still another parallelogram linkage which comprises the rod 38, the X-ray tube and cone, rod 68 and shaft 40, and which serves to turn the tube on its own axis and direct the center ray through the nodal point, the tube being

mounted in suitable bearings so as to permit such movement about its longitudinal axis.

I have provided a clamping means 70 and 71 that is used to hold shaft 40 parallel to axle 27 when the tube-supporting assembly is raised or lowered for focal adjustment, thereby eliminating the necessity of complicated adjustment; the screw and wheel assembly 71 being mounted upon the casting 41a, and the member 70 with the arcuate slot being mounted upon the adjustable bracket 41. Thus, when changing the focal adjustment, the wheel 71 is tightened so as to maintain the parallel relation between shaft 40 and axle 27, and the set screws 40d, 58e and 41d are loosened so as to permit such adjustment; then when the focal adjustment has been made, the set screws are tightened and the wheel 71 is freed so as to permit the screw 71 to move up and down in the arcuate slot 70 during operation of the members. The strap 38a connects the castings at the ends of the shaft 40 and the rod 58 so as to maintain them at constant distance apart when the clamp screws are loosened.

The features of novelty and special utility in this machine are believed to be quite numerous.

They include, for instance, the compound parallelogram linkage for the cassette carrier, and the compound parallelogram linkage for the tube, for operation in the manner above explained; the means of increased amplitude and the means for adjusting the same for all degrees; the supporting of the entire machine, as a self-contained structure, at the base thereof with low center of gravity; the location of the drive connections and the means of amplitude adjustment also at the bottom thereof; the special adaptability of this machine structure to various technique, with marked flexibility, including the older conventional manner of operation, the comparative simplicity of design and operation; the comparative low cost of manufacture; the improved form of grid; the improved means of adjustment for taking stereoscopic radiographs; the improved means for effecting spiral path of movement with increased assurance of maintaining the clarity of the image of the body section being radiographed; the conveniently adjustable bed for supporting the body of the patient; and the compact and dependable form and arrangement of all of the various features of construction herein described.

It is believed that this machine embodies in a feasible and efficient manner all essential and important features of construction and operation and eliminates complications that have rendered other such machines impractical. This machine is capable of all of the possible uses of the older conventional machine and embodies also the further possibility of operating the cassette and the target of the tube in circular paths in parallel flat horizontal planes in a dependable manner, together with numerous features of advantage above noted and suggested.

What I claim is:

1. In an X-ray machine, the combination of an X-ray tube, a carrier for an X-ray sensitive film, upright supporting means for said tube and film carrier, said supporting means having a universal bearing at a nodal point corresponding to the objective plane, a rotatable base upon which said supporting means is mounted and having operative connection with the lower end of said supporting means, and operating means connected to said base for effecting such movement of said supporting means about its nodal point that the

film and the target of the tube will simultaneously describe paths in planes parallel to the objective plane and thereby effect mechanically a virtual focus of the rays from the tube in the objective plane.

2. In an X-ray machine, the combination of an X-ray tube, a carrier for an X-ray sensitive film, upright supporting means for said tube and film carrier, said supporting means having a universal bearing at a nodal point corresponding to the objective plane, a rotatable base upon which said supporting means is mounted and having adjustable connection with the lower end of said supporting means for varying the amplitude, and operating means connected to said base for effecting such movement of said supporting means about its nodal point that the film and the target of the tube will simultaneously describe circular paths in planes parallel to the objective plane and thereby effect mechanically a virtual focus of the rays from the tube in the objective plane.

3. In an X-ray machine, the combination of an X-ray tube, a carrier for an X-ray sensitive film, upright supporting means for said tube and film carrier, said supporting means having a universal bearing at a nodal point corresponding to the objective plane, a rotatable base upon which said supporting means is mounted and having diametrically slidably adjustable connection with the lower end of said supporting means, and operating means connected to said base for effecting such movement of said supporting means about its nodal point that the film and the target of the tube will simultaneously describe circular paths parallel to the objective plane and thereby effect mechanically a virtual focus of the rays in the objective plane.

4. In an X-ray machine, the combination of an X-ray tube, a carrier for an X-ray sensitive film, supporting means for said tube and film carrier, said supporting means having a single universal bearing at a nodal point corresponding to the objective plane, means including compound parallelogram linkage for effecting such movement of said supporting means about its nodal point that the film and the target of the tube will simultaneously describe circular paths in planes parallel to the objective plane and thereby effect mechanically a virtual focus of the rays in the objective plane.

5. In an X-ray machine, the combination of an X-ray tube, a carrier for an X-ray sensitive film, supporting means for said tube and film carrier, said supporting means having a universal bearing at a nodal point corresponding to the objective plane, a horizontally disposed turn-table upon which said supporting means is mounted and having vertical swivel connection with the lower end of said supporting means, said supporting means including an extension at the lower end thereof occupying a fixed horizontal plane with respect to said turn-table, and operative connections between said extension and said tube and film carrier whereby movement of said supporting means about its nodal point will cause the film and the target of the tube to simultaneously describe circular paths in planes parallel to the objective plane and thereby effect a virtual focus of the rays in the objective plane.

6. In an X-ray tube, the combination of an X-ray tube, a carrier for an X-ray sensitive film, supporting means for said tube and film carrier, said supporting means having a universal bearing at a nodal point corresponding to the objective plane, a horizontally disposed turn-table upon

which said supporting means is mounted and having vertical swivel connection with the lower end of said supporting means, said supporting means including an extension at the lower end thereof occupying a fixed horizontal plane with respect to said turn-table, and operative connections including compound parallelogram linkage between said extension and said tube and film carrier whereby movement of said supporting means about its nodal point will cause the film and the target of the tube to simultaneously describe circular paths in planes parallel to the objective plane and thereby effect a virtual focus of the rays in the objective plane.

7. In an X-ray machine, the combination of an X-ray tube, a carrier for an X-ray sensitive film, supporting means for said tube and film carrier, said supporting means having a universal bearing at a nodal point corresponding to the objective plane, a horizontally disposed turn-table upon which said supporting means is mounted and having vertical swivel connection with the lower end of said supporting means, said supporting means including an extension at the lower end thereof occupying a fixed horizontal plane with respect to said turn-table, compound parallelogram linkage connection between said extension and said film carrier, and means of operative connection between said extension and said tube, whereby movement of said supporting means about its nodal point will cause the film and the target of the tube to simultaneously describe circular paths in planes parallel to the objective plane and thereby effect a virtual focus of the rays in the objective plane.

8. In an X-ray machine, the combination of an X-ray tube, a carrier for an X-ray sensitive film, upright supporting means for said tube and film carrier, said supporting means having a universal bearing at a nodal point corresponding to the objective plane, a turn-table upon which said supporting means is mounted and having diametrically slidably adjustable connection with the lower end of said supporting means, and means operable by said turn-table for effecting progressively continuous adjustment of said slidable connection so as to effect a more nearly complete blurring of shadows outside of the objective plane and for effecting such movement of said supporting means about its nodal point that the film and the target of the tube will simultaneously describe circular paths parallel to the objective plane so as to effect mechanically a virtual focus of the rays in the objective plane.

9. In an X-ray machine, the combination of an X-ray tube, a carrier for an X-ray sensitive film, upright supporting means for said tube and film carrier, said supporting means having a single universal bearing at a nodal point corresponding to the objective plane, means located upon opposite sides of said bearing for effecting vertical adjustment of said bearing so as to vary the elevation of the nodal point, and means for effecting such movement of said supporting means about its nodal point that the film and the target of the tube will simultaneously describe circular paths in planes parallel to the objective plane and thereby effect mechanically a virtual focus of the rays in the objective plane.

10. In an X-ray machine, the combination of a holder for an X-ray tube, a holder for an X-ray sensitive medium, upright supporting means for said holders, said supporting means having a universal bearing at a nodal point corresponding to the objective plane, a base,

a rotatable turn-table upon said base and upon which said supporting means is mounted and having operative connection with the lower end of said supporting means, operating means connected to said turn-table for effecting such movement of said supporting means about its nodal point that the sensitive medium and the target of the tube will simultaneously describe circular paths in planes parallel to the objective plane and thereby effect mechanically a virtual focus of the rays in the objective plane, a bed mounted upon said base above said holder for the sensitive medium, and a roller body-supporting table top horizontally disposed upon said bed in the region of the objective plane and adapted for transverse rolling adjustment thereupon.

11. In an X-ray machine, the combination of a holder for an X-ray tube, a holder for an X-ray sensitive medium, upright supporting means for said holders, said supporting means having a universal bearing at a nodal point corresponding to the objective plane, a base, a rotatable turn-table upon said base and upon which said supporting means is mounted and having operative connection with the lower end of said supporting means, operating means connected to said turn-table for effecting such movement of said supporting means about its nodal point that the sensitive medium and the target of the tube will simultaneously describe circular paths in planes parallel to the objective plane and thereby effect mechanically a virtual focus of the rays in the objective plane, a casing mounted upon said base and enclosing said holder for the sensitive medium and the operating means and operative connections, a body-supporting table top horizontally disposed upon the upper surface of said casing in the region of the objective plane, and roller means between said upper surface and table top permitting transverse rolling adjustment of the table top.

12. In an X-ray machine, the combination of an X-ray tube, a carrier for an X-ray sensitive film, a bracket for said tube, means for supporting said film-carrier and tube bracket, said tube bracket being rotatably adjustable upon said supporting means about a horizontal axis so as to occupy distinctly different positions, means permitting longitudinal adjustment of said tube upon its bracket so as to occupy spaced positions for taking stereoscopic radiographs, and unitary means of support for said tube upon said brackets during longitudinal adjustment thereof in either of said rotatable adjustments.

13. In an X-ray machine, the combination of an X-ray tube, a carrier for an X-ray sensitive film, upright supporting means for said tube and film carrier, said supporting means having a universal bearing at a nodal point correspond-

ing to the objective plane, operating means upon which said supporting means is mounted and being operatively connected thereto for effecting such movement thereof about its nodal point that the film and the target of the tube will simultaneously describe paths in planes parallel to the objective plane and thereby effect mechanically a virtual focus of the rays from the tube in the objective plane, and automatically compensating means for maintaining said tube in proper angular position at all times during such operation of the tube and film.

14. A construction containing the elements in combination defined in claim 13 and in which said last-named means consists of a parallelogram linkage including said supporting means and said tube bracket.

15. A construction containing the elements in combination defined in claim 8 and in which the means for effecting progressively continuous adjustment of said slidably connection is disconne-

16. In an X-ray machine, the combination of an X-ray tube, a carrier for an X-ray sensitive film, upright supporting means for said tube and film carrier, said supporting means having a universal bearing at a nodal point corresponding to the objective plane, a rotatable base upon which said supporting means is mounted and having operative connection with the lower end of said supporting means, and operating means connected to said base for effecting such movement of said supporting means about its nodal point that the film and the target of the tube will simultaneously describe paths in planes parallel to the objective plane and thereby effect mechanically a virtual focus of the rays from the tube in the objective plane, a bed mounted upon said base above the carrier for the sensitive film, and a roller body-supporting table top horizontally disposed upon said bed in the region of the objective plane and adapted for transverse rolling adjustment thereupon.

17. In an X-ray machine, the combination of an X-ray tube, a carrier for an X-ray sensitive film, upright supporting means for said tube and film carrier, said supporting means having a single universal bearing at a nodal point corresponding to the objective plane, means for effecting vertical adjustment of said bearing so as to vary the elevation of the nodal point, and means for effecting such movement of said supporting means about its nodal point that the film and the target of the tube will simultaneously describe circular paths in planes parallel to the objective plane and thereby effect mechanically a virtual focus of the rays in the objective plane.

GEORGE H. CHAMBERLAIN, JR.
